UNITED STATES PATENT OFFICE

2,405,548

COUNTER PASTING MACHINE

Charles Martin Bagshaw, Leicester, England, assignor to United Shoe Machinery Corporation, Flemington, N. J., a corporation of New Jersey

Application December 4, 1943, Serial No. 512,924
In Great Britain January 27, 1943

26 Claims. (Cl. 12—80)

1

This invention pertains to improvements in apparatus for use in applying a coating to shoe parts and is illustrated herein as embodied in a counter pasting machine of the character illustrated in application Serial No. 550,764, filed August 23, 1944 (now United States Letters Patent No. 2,370,917, granted March 6, 1945), in the names of Fred Ricks and Charles M. Bagshaw.

It is customary to apply a coating of adhesive to the inside and outside surfaces of premolded counters so that when they are inserted between the outer layer of the shoe upper materials and the lining at the heel end of the shoe, in assembling the upper materials on a last, and the whole is subjected to the subsequent heel seat lasting operations, a composite back part will be formed the component parts of which will not slip relative to each other in the finished shoe. In the above-mentioned application there is illustrated and claimed a machine for applying adhesive, hereinafter called paste, to a premolded counter, in a semiautomatic manner. Such a machine will frequently be used in conjunction with heel seat lasting machines to furnish freshly coated counters at a rapid rate and in such timed relation to the heel seat pulling-over and lasting operations that a freshly coated counter will constantly be in readiness for the succeeding operations. The aforesaid prior machine comprises a pair of oppositely disposed parallel applicator brushes, one of which is furnished with paste, and between which the diverging legs of the counter are moved in succession, a reciprocating crosshead being provided for moving the counter linearly with respect to the applicator brushes, open end first, to advance one leg between the brushes, then to rotate the counter as the rounded end reaches the brush engaging the inner side of the counter, and then to continue the linear movement of the counter in the same direction, rounded end first, to draw the other leg between the brushes. The movement of the crosshead is then reversed and, hence, carries the counter back to its starting point, the linear and rotational movements of the counter being duplicated in the opposite direction so that two coats of paste are applied. For reasons assigned in the prior application, it is desirable to omit the application of paste along the top and bottom marginal edges of the counter from the rounded heel end forwardly and also part way around the curved forward ends of the legs. Accordingly, in the prior machine, shielding members were provided for effecting protection of these areas. The shielding means provided for protecting the

2

top and bottom edges was entirely satisfactory, but that which protected the forward curved marginal end portions of the legs necessarily extended transversely of the counter and applicator brushes, and each time the counter moved between the applicator brushes the transversely extending shielding means were given a heavy coating of paste. The movement of the crosshead spattered the paste and made it necessary to clean the machine frequently to avoid soiling the work. Moreover, while the aforesaid machine was provided with shielding means for protecting the curved forward outside surfaces of the diverging legs of the counter adjacent to their end portions, no means was provided for protecting the corresponding areas at the inside of the legs.

An object of this invention is to provide a semiautomatic adhesive applying machine by the use of which paste may be applied to the inside and outside surfaces of a premolded counter, provision being made for applying a coating to the central portion of the inside and outside surfaces while omitting the marginal portions extending from the rounded heel end forwardly and around the curved ends of the legs without employing shielding means to protect the curved forward ends, thereby improving the cleanliness of the machine and rendering it less complicated.

In its broadest aspect, invention resides in applicator means, means for supporting a shoe part adjacent to the applicator means, and means for causing relative movement of the applicator means and the supporting means to bring the shoe part into contact with the applicator at a point spaced from the end of the shoe part, in the direction of relative approach, and then to move one over the other to spread the paste over an adjacent portion of the shoe part, leaving a clean margin. More specifically, this is accomplished in the instant machine in a novel manner by a counter supporting and clamping means, applicator means, and means for moving the counter supporting and clamping means transversely of a part of the applicator means in such a position with respect to the direction of movement that the marginal portions of the legs of the counter adjacent to their ends lie outside the field of action of the applicator means. Thus, they pass above and beyond the applicator means without engaging the same and hence without receiving a coating of paste. During the application of the coating to the one surface of the counter, means associated with the means for moving the counter moves another part of the

applicator means, adapted to coat the other surface of the counter, in timed relation to the movement of the counter to move this applicator means into and out of engagement with the legs at points substantially opposite the points of engagement and disengagement of the one surface of the counter with the one part of the applicator.

The applicators consist of a pair of brushes, one of which is movable, one of the brushes being supplied with paste and the other receiving a supply of paste from the first brush during those periods when no work is passing between them. The movable one of the brushes receives paste directly from a paste container, and, in accordance with a feature of the invention, means is provided for holding the movable brush in contact with the fixed brush for a predetermined time, then for moving the movable brush relative to the fixed brush to admit the work, and then through a predetermined path to cause it to engage predetermined portions of the counter. To render the supply of paste uniform, means is provided for holding the container at a fixed position with respect to the median of the range of movement of the movable brush during the latter part of its movement, thereby to prevent undue pressure between the brush and the container.

In the illustrated machine, the counter is placed astride a support which has a contour which is substantially complementary to the contour of the inside of the counter and clamping means are provided for holding the counter on the support. The natural springiness of the counter causes the legs to grip the support even after the clamping means are released, and still another feature of the invention resides in means associated with the support which will automatically disengage the counter when the clamping means are released.

In the machine disclosed the counter is moved in a linear direction in a path contiguous to an applicator and supported during its linear movement in positions in which those portions of its surface near the ends of its legs will move beyond the field of action of the applicator without engaging the applicator, thereby leaving these portions free of paste. Simultaneously, an applicator for applying paste to the other surface of the counter is moved in timed relation to the movement of the counter to cause it to engage and disengage this other surface of the counter at points spaced from the ends of the legs, thereby leaving corresponding uncoated areas on both surfaces of the counter near its ends.

Other features of the invention, in addition to those above referred to and including improved details of construction and combinations of parts, the advantages of which will be clear to those skilled in the art, will be hereinafter more particularly described with reference to the accompanying drawings, in which

Fig. 1 is a view in elevation of the right-hand side of a machine in which the invention is embodied;

Fig. 2 is a somewhat enlarged view of one of the applicator brushes and a paste container associated therewith, showing the details of a valve for controlling the quantity of paste supplied to the brush;

Fig. 3 is a plan view of the rear portion of the machine, showing the driving pulleys and belt shifting mechanism;

Fig. 4 is a larger scale view of the machine in elevation as seen from its front end with parts

in section, taken transversely of the machine on the line IV—IV of Fig. 1;

Fig. 5 is a vertical section on the line V—V of Fig. 4, showing the details of the counter clamping means;

Fig. 6 is a vertical section on the line VI—VI of Fig. 4;

Fig. 7 is a plan view on a larger scale of the front portion of the machine, illustrating the initial position of the counter holding and clamping means, the upper applicator brush being omitted;

Fig. 7a is a section on the line VIIa—VIIa of Fig. 7 taken through a counter holding member;

Fig. 8 is a perspective view of a molded counter after it has been operated upon by the machine, showing the body portion coated and the marginal portions uncoated;

Fig. 9 is a large scale view in right-hand side elevation, illustrating the position of the upper applicator brush as the counter is advanced into adhesive applying position; and

Fig. 10 is a section on the line X—X of Fig. 7, illustrating the details of part of the counter clamping means.

A machine of this general type is illustrated and described in the above-mentioned application Serial No. 550,764, Patent No. 2,370,917. However, since numerous changes have been made in the construction of the aforesaid machine in conjunction with the novel features of the present invention, the following description of the machine will be given in sufficient detail to afford a clear understanding of the invention with a minimum of reference to the prior machine.

Referring to Figs. 1 and 4, a rectangular channel-shaped frame 10 is fastened in a horizontal position upon the upper end of a vertical pedestal 12 which rises from the floor and forms a base for the machine. The rectangular frame is adapted to support in operative relation means for applying a coating of adhesive, hereinafter called paste, to a preformed counter and means for holding the counter and moving it progressively with respect to the applicator means in such a manner as to apply paste to both the inside and outside surfaces of the counter, as illustrated in Fig. 8, except for the top and bottom marginal portions extending forwardly from the back part to and around the curved open ends, which are left free of paste.

The means for applying the paste consists of a pair of juxtaposed brushes 14 and 16 (Fig. 4) mounted for rotation with parallel shafts 18 and 20 journaled in bearings 22 and 24, respectively. The bearing 24 is formed in an upwardly projecting bracket 26 fastened to the left side of the frame 10. The bearing sleeve 22 is pivotally mounted at 28, for reasons which will appear hereinafter, in a forked extension 27 of the bracket 26 and is urged to turn in a counter-clockwise direction about its pivot by a spring-pressed plunger 30. The plunger 30 is slidably seated in a bore 32 formed in the upper end of the bracket 26 beneath the bearing sleeve 22 and a spring 34 is disposed in the bore 32 behind the plunger, a portion of the spring extending into a bore 36 formed in the lower end of the plunger. Pulleys 38 and 40 are fixed to the shafts 18 and 20 and are connected, as will be seen by reference to the prior application, to a source of power (not shown herein) for rotating the brushes 14 and 16 in opposite directions, as indicated by the arrows in Figs. 1 and 4. The brush 14 is adapted to apply a coating of paste to the outside surface

of the counter and is about 6 inches in diameter, having relatively long, flexible bristles which will conform readily to the shape of the counter. The brush 14 rotates in a clockwise direction (Fig. 2) at about 60 R. P. M. The brush 16 is adapted to apply paste to the inside surface of the counter and is about 2½ inches in diameter, having relatively long, flexible bristles which will conform to the inside of the counter. This brush rotates at about the same peripheral speed as the brush 14 but in a counterclockwise direction and it is to be observed that the shafts of the brushes are close enough together so that the bristles of the two brushes intermesh by an appreciable amount (Fig. 1). The brush 14 is furnished with paste from a receptacle 42 (Fig. 2) and the brush 16 receives paste indirectly from the brush 14 during those periods when no work is being passed between the brushes.

The receptacle 42 (Fig. 4) is mounted above the topmost point of the brush 14 in substantially tangential relation thereto upon a shelf 44 which is fastened to an arm 46 pivoted at 48 to a post 50 bolted to a bracket 52 which, in turn, is bolted to the right-hand side of the frame 10. The bottom side of the paste receptacle 42, as will be seen by reference to Fig. 2, is provided with a rectangular opening 54 through which paste may run onto the bristles of the brush 14. The size of the opening 54 may be controlled in accordance with the viscosity of the paste, to permit a larger or smaller quantity to flow through it, by a slide valve 56 having an opening 58 therein corresponding in size to the opening 54 in the bottom of the receptacle. The slide valve 56 consists of a flat plate which is slidable in a groove 57 (Fig. 4) formed in the upper face of the shelf 44. The valve 56 has at one end an upwardly projecting flange 60 which serves in co-operation with a pivoted lever 62 to slide the valve to the right or left to open or close the valve. As will be seen by reference to Figs. 1 and 2, a plate 64 forming part of the lever 62 and having a bifurcated end 66 is pivoted at 68 to a bracket 70 fastened to the side of the receptacle 42 in such a position that the upper end of the flange 60 projects into the bifurcation. The lever 62 is rigidly fastened by screws 72 to the plate 64 in a position to lie beside one end of the receptacle 42, as seen in Fig. 1, and on the upper end of the lever 62 is a pointer which may be moved over a scale 74 marked on the side of the receptacle. The graduations on the scale represent valve openings for varying conditions of viscosity. A small knob 76 formed on the pointer serves as a hand hold to move the pointer over the scale in one direction or the other. It was found that when the valve 56 was closed the ends of the bristles of the brush 14 would rub against the bottom face of the valve and cause some wear, which is undesirable, and, furthermore, when the machine was at rest, the under surface of the valve would deflect the bristles and, if left in this position for any length of time, a permanent distortion of the ends of the bristles would be brought about. To avoid this, a recess 78 (Fig. 2) is formed in the bottom side of the valve plate 56 and in the shelf 44 to accommodate the projecting ends of the bristles.

A counter 79, as shown in Fig. 8, is preformed and has diverging legs joined by a rounded back part, and in the illustrated machine means is provided for moving the counter, open end first, in a linear direction to advance one leg between the brushes 14 and 16 until the inner surface

to project into a circular groove 112 cut into the disk 108. It is to be observed (Fig. 6) that, as in the prior machine, to permit movement of the bearing beneath the shaft 20 during the linear movement of the counter holding and clamping means, the bearing 90 is made slightly less than semicircular so that its upper extremities terminate below the shaft 20.

The clamping means 82 which cooperates with the supporting means 80 in holding the counter, during its linear movement, is mounted at the right-hand side of the brush 16, as viewed in Fig. 4, upon a horizontal shaft 114 which is rotatably mounted in a split bearing 116 (Fig. 4), the latter being formed integral with a post 117 (Fig. 9) on the crosshead 92. The axis of the shaft 114 is coincident with the axis of rotation of the hub 88. The split bearing 116 is provided with a pair of bosses 118 (Fig. 7) which are joined by a bolt 120, the bolt passing loosely through one of the bosses and being threaded into the other. A spring 122 is placed between the head of the bolt 120 and the boss through which the bolt passes loosely so that by rotation of the bolt the elements of the bearing may be drawn together about the shaft 114 yieldably to grip the shaft, the adjustment of the bolt affording means for varying the frictional resistance to rotation of the shaft. On the inner or left-hand end of the shaft 114 there is formed a rectangular shaped projection 124 which terminates at its extreme left end in a block 126 substantially V-shaped in side elevation (Fig. 5) and corresponding to the block 84 except for the fact that there is no V-shaped recess therein. The block 126 has a sloping peripheral surface 128 (Fig. 7) over which the marginal edge of the counter lies. The clamping means consists of a pair of thin, elongated plates 130 (Figs. 5 and 7) which are yieldably urged toward the sloping surface 128 of the block 126, thereby to engage the marginal edges of the counter and hold them in against the diverging legs of the substantially V-shaped block 126. Each plate 130 has a split pin 132 (Fig. 7) formed near one edge between its ends and which is adapted frictionally to fit into a bore 134 formed in a supporting member 136. Each supporting member 136 is, in turn, forked and pivotally mounted upon the ends of a pin 138 which is journaled in a boss 140 formed on the rectangular member 124. By the aforesaid construction, each plate 130 may turn about the axis of the pin 132 to compensate for variations in the thickness of the edges of the counter along the legs thereof and may be moved to and from the periphery of the V-shaped block 126 to permit introduction and removal of the counter. To hold the plates 130 yieldably in engagement with a counter on the block 126, a pair of springs 142 and 144 (Fig. 5) is provided, the opposite ends of the springs being hooked between the opposite ends of a pair of bars 146 which, in turn, are fastened by screws 148 to the supporting members 136. It is to be observed that the plates 130 engage the marginal edge of the counter from the rounded, closed end forwardly to the open ends of the legs but do not extend around the curved forward ends of the legs as in the machine of the prior application. Hence, these plates provide means for shielding only the upper margins of the counter.

Mounted on the rectangular member 124, which is integral with the shaft 114 of the counter clamping means 82, and slideable thereon transversely to the axis of said shaft is a wedge-shaped block 174 (Fig. 5) which has a bifurcation 176

at its small end adapted telescopically to fit over the rectangular member. The wedge-shaped block 174 has a pair of sloping surfaces 178 adapted to engage a pair of rollers 180 (Fig. 4) which are mounted for rotation on a pair of posts 182, the latter being fastened to and projecting inwardly from the pivoted supporting members 136. Hence, by forcing the wedge-shaped block 174 inwardly between the rollers 180 the plates 130 may be moved apart against the action of the springs 142 and 144 to release the counter. When the force applied to the block 174 is withdrawn, the plates are urged together by the springs 142 and 144 to clamp the upper edge of the counter in place. To assist in guiding the wedge-shaped block 174, a hollow stem 173' (Fig. 5) is provided in the bifurcation 176 of the block and is slideable in a bore 175 formed in the member 124. A spring 173 disposed in the hollow stem bears against the bottom of the bore 175 and assists in moving the block 174 from between the rollers 180. The means, including a stop disk 234, for forcing the wedge-shaped block 174 inwardly to separate the plates will be described hereinafter.

In the prior machine it was found that some counters had so much springiness that they hugged the counter holding and clamping means even after the clamping plates were withdrawn so that it was a little troublesome to remove the coated counters without taking hold of the pasted areas. In order to overcome this situation, the rounded rear end portion, denoted 158, of the V-shaped block 126, as shown in Fig. 10, is made separable therefrom, and is yieldably urged away from the block by a pair of parallel plungers 160 which are slidably received in bores 162 formed part way through the V-shaped block. The plungers 160 have reduced ends 164 which are fixed in the rounded end 158. In the bores 162 behind the plunger are disposed springs 170 which urge the plungers out of the block and consequently hold the rounded end 158 spaced from the block. In alignment with the bores 162 are smaller passages which extend through to the front face of the block and through these pass reduced necks 166 formed on the rear ends of the plungers. A pair of collars 172 are fixed to the reduced necks of the plungers and by contact with the front face thereof prevent the springs 170 from forcing the rounded end 158 too far to the rear of the V-shaped block 126.

When the counter is mounted on the counter holding and clamping means, it is pushed into place with sufficient force to press the rounded end 158 into engagement with the major portion of the block 126. The counter is held there manually until the clamping means 130 comes into effect and grips the counter with sufficient force to hold it in place against the tendency for the rounded end 158 to disengage it from the block 126. When the clamping means is released, after the pasting operation, the rounded end 158 will spring rearwardly, thus disengaging the counter. Hence, if there is a tendency for the counter to cling to the supporting and clamping blocks, the rounded end 158 will disengage the counter so that it may readily be withdrawn by grasping the uncoated flange 87, for example.

A pulley 184 (Figs. 4 and 7) similar to the pulley 100 is fastened to the shaft 114 and is provided with a pair of grooves 186 in which the ends of a chain 188 are fastened (Fig. 6), thus providing means for rotating the shaft, and consequently the counter clamping means. The right hand flange of the pulley, as seen in Fig. 4,

is somewhat larger in diameter than the rest of the pulley and is held against the bearing 116, thereby to prevent axial movement of the shaft 114, by the overlapping heads of screws 185 (Fig. 7) which are threaded into the bearing.

The crosshead 92 which carries the counter holding means 80 and clamping means 82 is mounted for movement transversely of the applicator brushes 14 and 16 upon a pair of horizontally disposed parallel rods 190 (Figs. 1 and 4), the latter being supported at their opposite ends on the rectangular frame 10. As illustrated in Fig. 1, a pair of posts 192 are formed integral with the frame 10 at the front of the machine and have openings 194 therein for the reception of the front ends of the rods 190. The rear ends of the rods 190 are supported by a corresponding pair of posts 196 which are formed integral with the rear end of the frame 10 and have openings 198 for the reception of the rear ends of the rods. The transverse or linear sliding movement of the crosshead 92 along the rods 190 from front to rear is accomplished in a manner to be described below to move the counter from its initial position at the front of the machine, with its open end toward the rear, toward the applicator brushes with the upper leg disposed at an angle of about 20° to the horizontal. Linear movement of the crosshead with the counter in this position brings the aforesaid leg into contact with the brush 16 which applies a coating to the inside of the counter at a point back of its leading edge, as will be seen by reference to Fig. 9, since the leading edge and the marginal portion adjacent thereto, represented by the reference character *m*, pass above and beyond the brush without making contact with its surface as the counter is moved horizontally to the rear toward the brush. Hence, this marginal portion remains uncoated. After contact is made between the counter and the brush, the crosshead continues its linear movement until the brush engages the closed, rounded end of the counter, whereupon means to be described causes rotation of the counter which brings the other leg of the counter into a position reversely inclined to that of the first leg of the counter, that is, so that the leg makes an angle of about 20° to the horizontal. After the rotation is completed, the crosshead resumes its linear movement and the second leg is drawn between the brushes and disengages the lower brush 16 at a point which precedes the trailing end of this second leg. Hence, a marginal portion on the second leg corresponding to the marginal portion *m* on the first leg is also left uncoated. During the coating of the inner surfaces of the legs, the outer surfaces are also coated, the upper brush 14 being moved up and down in timed relation with the movement of the counter so that contact is made with the first leg at a point spaced from the advancing end and substantially opposite to the contact of the brush 16 with the inner surface of the leg, and contact is broken, by raising the brush 14, at a corresponding point on the opposite leg. The mechanism for accomplishing the linear movement of the crosshead and the rotational movement of the counter support and clamping means will now be described.

At the front end of the machine, upright posts 200 (Figs. 1 and 5) are mounted on the frame 10 and upon the upper ends of these posts are fixed inwardly extending horizontal studs 202 and 204 (Fig. 7). Rotatable on the horizontal studs are pulleys 208. At the rear of the machine, a pair of sprockets 212 are mounted on a level with the

pulleys 208 on a horizontally disposed shaft 214 (Fig. 1) which is journaled at the upper ends of a pair of upright posts 216 which rise vertically from the frame 10. The aforementioned chains 106 and 188, as heretofore explained, are connected at their opposite ends to the pulleys 100 and 184 attached to the counter holding and clamping means, respectively. Starting at these pulleys, the chains pass over the top of the pulleys and are carried to the left of the crosshead, as seen in Fig. 1, and around the pulleys 208, thence lengthwise of the machine beneath the brush shafts 18 and 20 and the sprockets 212 and back to the pulleys 100 and 184. In order to keep the chains taut, the posts 200 at the forward end of the machine are pivotally supported at their lower ends upon bolts 218 (Fig. 9) so that they may be moved forward or backward. Each post 200 is provided with an elongated slot 220 through which there is passed a clamp bolt 222 which serves to lock the posts in such a position that the chains are held in whatever degree of tautness is desired.

Upon the stud 202 at the front end of the machine there is fastened a bracket 224 (Figs. 7 and 9) which extends upwardly and inwardly from the post and has a horizontal arm 226 formed integral therewith through one end of which there is threaded a rod 228 the position of which may be adjusted by turning it in the arm 226 and locking it in place by a nut 230. At the end of the rod there is formed a yoke 232 in which there is journaled a stop-disk 234. As will be seen by reference to Fig. 5, the stop-disk 234 is adapted to engage the wedge-shaped block 174 when the cross-head is at its initial position at the front of the machine, thereby holding the counter clamping plates 130 away from the V-shaped block 126, and hence the operative may place the counter astride the V-shaped blocks 126 and 84. In placing the counter in position astride the aforesaid blocks, the inturned bottom flange 87 of the counter 79 is inserted in the groove 94 of the V-shaped block 84 and the upper marginal edge of the counter is disposed along the sloping surface 128 of the V-shaped block 126, the operative pushing the counter forward into engagement with the blocks with sufficient force to move the rounded end 158 (Fig. 10) of the V-shaped block 126, which is normally held away therefrom at this position, into engagement with the block and holds the counter thus until the machine is started and the crosshead moves away from the stop-disk 234 far enough to permit the counter clamping plates 130 to come into engagement with the upper margins of the legs of the counter. To start the machine, the operative pulls forwardly a rod 236 (Fig. 1), having a knob 238 for conveniently gripping it, and this, as will be seen by reference to Fig. 3, moves a bell-crank lever 240 in a counterclockwise direction about a pivot 242. Alternatively, the rod 236 may be pulled forward by a chain 239 connected to the rod, as seen in Fig. 5, and to a treadle-operated lever 241, the treadle being located below the machine but not shown herein. The lever 240 is retained in this forward position so that the machine continues in operation once the rod 236 has been pulled, without holding it, by a spring 243 stretched between the lever and the frame in a position to cross the center of the pivot 242, as explained in the prior application, to bias the lever in one position or the other. A fork 244 (Fig. 3) is formed in the end of one arm of the lever 240 which co-operates with a pin 246, the latter being fixed to a horizontally disposed plate

11

243 which is slidable widthwise of the machine upon a pair of rods 250. The rods 250 are journaled in spaced relation at their opposite ends in substantially triangular shaped upwardly extending webs 252 (Fig. 1) formed at the rear of the frame 10, the webs having bearings 254 formed at their upper ends for pulleys which serve to connect the machine to a motor (not shown) placed near the base of the machine, as illustrated in the prior application. On the horizontal plate 248 there are a pair of belt shifters 256 and 258 which extend forwardly and rearwardly, respectively. A horizontal shaft 260 is journaled in the bearings 254 and has on it three pulleys 262, 264, and 266. The middle one of these pulleys 264 is fastened to the shaft 260 and when rotated by a belt causes rotation of the shaft 260 which, in turn, drives the shaft 214 by way of a pair of meshing gears 268 and 270, the former being fastened to the shaft 260 and the latter to the shaft 214. The pulleys 262 and 266 are free to turn on the shaft 260 and each has a pair of grooves in its peripheral surface for reasons which appear in the prior application. A crossed belt 272 is carried by the pulley 262 and an open belt 274 is carried by the pulley 266. These belts, as will be seen by reference to the prior application, are connected to a source of power (not shown) and may be shifted by movement of the belt shifters 256 and 258 to drive the pulley 264 in a counterclockwise or a clockwise direction and hence to move the upper run of the chains 106 and 188 either in a right-hand direction or a left-hand direction, thereby to reciprocate the crosshead linearly with respect to the applicator brushes. As explained in the prior application, the crosshead has projecting from its rear side a bolt 276 (Figs. 1 and 9) which will engage the lever 240 as the crosshead moves to the extreme right-hand position automatically to shift the open belt 274 onto the idle pulley 266 and simultaneously to shift the crossed belt 272 from the idle pulley 262 onto the driving pulley 264, thereby automatically to reverse the movement of the machine and cause the crosshead to return to the front of the machine. Hence, when the crosshead is initially started it will travel from the front end of the machine to the back end and then reverse itself and travel back to the front end where it will automatically be brought to a stop by the following mechanism. At the front end of the crosshead and projecting downwardly from its underside is a boss 284 (Fig. 5) which, as the crosshead moves to its initial position, engages a collar 286 fastened to the rod 236 which pushes the rod forward a sufficient distance to move the lever 240, and consequently the belt shifter, to a neutral position so that the machine comes to rest. Simultaneously, a latch 278 (Fig. 9), which is pivotally attached to the front end of the crosshead and is spring pressed downwardly by a torsion spring 280, engages a pin 282 which projects horizontally from the inside of the left-hand post 192. The engagement of the latch and pin holds the crosshead in its forward position. Attached to the latch 278 is a downwardly extending arm 288 which lies in the path of the collar 286 and rides over the latter on the return of the crosshead 92. Hence, when the rod 236 is pulled forward to start the machine, the collar 286 will engage the arm 288 and move it upwardly, thus disengaging the latch 278 from the pin 282 and releasing the crosshead 92 so that it may be moved linearly by the chains 106 and 188.

12

At one point in the linear movement of the crosshead, the counter support and the clamping means are rotated, as in the previous machine, when the rounded, closed end of the counter reaches the applicator brushes. This is accomplished, as in the prior machine, by a pair of levers 290 and 292 (Figs. 1, 6 and 9) which are pivotally fastened to the frame 10 at 294 and 296, the lower ends being urged toward each other by a spring 298 which is fastened between them. The upper ends of the levers bear on the underside of a horizontal bar 300 (Figs. 1 and 9), which is fastened to the crosshead and moves therewith, and are adapted to engage notches 302 formed in the underside of the bar. The respective levers 290 and 292 have offset cam blocks 291 and 293 (Fig. 6). During movement of the crosshead toward the rear of the machine, that is, to the right as seen in Fig. 1, the lever 292 will engage the right-hand notch 302 and arrest the linear movement, whereupon continued movement of the chains 106 and 188 will cause rotation of the counter holder and clamping means about the axis of the shaft 114 until a stop screw 304 (Fig. 6) threaded through one of a pair of lugs 306 formed integral with the disk 108 strikes the cam block 291 lever and pushes it down out of the notch 302, whereupon the crosshead will continue its linear movement to the rear of the machine. As in the prior machine, the movement of the counter holding and clamping means during their approach to the brushes and after they have passed beyond the applicator brushes is restricted to linear movement by the frictional resistance to rotation of said holding and clamping means afforded by tightening the bolt 120 which draws the split bearing 116 about the shaft 114. When the lever 292 rises into the notch 302 as the crosshead moves toward the center of the machine, the frictional resistance to rotation of the shaft 114 in its bearing 116 is overcome and rotation takes place until the lever 292 is moved out of the notch. On the reverse movement of the crosshead from the back of the machine to the front of the machine, that is, from right to left as seen in Fig. 1, the lever 290 performs a similar function so that the counter is again rotated as it passes the applicator brushes until a screw 305 pushes it down out of its notch.

In the present machine, in contrast to that described in the prior application, the counter holding and clamping means are so positioned that the leg which is being operated upon makes an angle of approximately 20° to the horizontal, that is, the direction of movement of the counter. In order to avoid displacement of the counter clamping and supporting means from this position when the wedge-shaped block 174 is brought into contact with the disk 234 at the front of the machine, a locating screw 308 is provided which is threaded through a boss 310 formed on the disk 108, as will be seen by reference to Fig. 6. The end of the locating screw 308 is adapted to engage the top surface of the horizontal bar 300 and hence to hold the counter clamping and supporting means in the proper position against any tendency to turn.

In the prior machine, the brush for applying paste to the outside of the counter was stationary. In the present machine, however, in order to prevent the application of paste to the outside marginal portions of the curved ends of the legs of the counters, the upper brush 14 is so mounted that it may be moved into and out of contact with the legs of the counter in timed relation with the movement of the counter transversely thereof.

To permit such movement, as heretofore described, the shaft 18 of the upper brush 14 is mounted in the sleeve bearing 22 (Fig. 4) which is tiltable to and from the lower brush 16 about the horizontal pivot 28. The movement of the brush 14 to and from the brush 16 is controlled by the combination of the spring 34 and a cam 312 (Fig. 9), the cam being fastened to the upper ends of a pair of vertical posts 314 which, in turn, are set into recesses formed in the sides of the post 117 on the crosshead 92, as seen by reference to Figs. 1 and 9, and held there by screws 315 (Fig. 1) and a through bolt 317. As will be seen by reference to Fig. 4, the shaft 18 extends beyond the right-hand side of the brush 14 and has mounted thereon a collar 316 and a freely rotatable sleeve 318 which is held against the under surface of the cam 312 by the spring 34 which urges the bearing sleeve 22, and consequently the shaft 18 of the brush 14, in a counterclockwise direction about its pivot 28. The lower surface of the cam 312 is so shaped that when the crosshead is at its initial position that portion of its surface designated *a* (Fig. 1) holds the brush 14 in engagement with the brush 16 in opposition to the spring 34 so that the brush 16 will receive paste from the brush 14. When the machine is started, the cam 312 moves to the right, as seen in Fig. 1, and the sleeve 318 follows the upward slope of the surface marked *b* so that when the leading end of the counter is approximately adjacent to the entrance side of the brushes the upper brush 14 will have risen to the position shown in Fig. 9. Hence, the brush 14 is separated from the brush 16 and it does not contact the leading end of the counter. At this position the sleeve 318 occupies the portion *c* of the cam. Further movement of the crosshead brings the sleeve 318 into engagement with the downwardly sloping surface *d* of the cam so that the brush 14 is brought into engagement with the outer surface of the counter and at the point *e* the brush 14 is held in a fixed position during the rotation of the counter. As the other leg of the counter is withdrawn from between the brushes the brush 14 is allowed to rise out of contact with the counter, just as the trailing marginal portion of the leg reaches the brushes, by the sloping surface *f*. Since the cam surface is symmetrical, on the reverse movement of the crosshead the brush 14 is actuated in the same manner.

During the movement of the brush 14 to and from the brush 16, the paste container 42 is moved upwardly, to prevent undue pressure of the brush against the paste container during the rising movement of the brush 14, by the co-operation of a cam roll 320 with that portion of the upper surface of the cam 312 designated *g*. Before the counter engages the brushes, the brush 14 is in engagement with the brush 16 to feed paste to it and the container is held in a depressed position, to maintain contact with the brush, by a dip in the cam surface at *h*. The cam roll 320 is freely pivoted on an arm 322 extending downwardly from the bottom side of the pivoted arm 46 upon which the container 42 rests. A fork 321 fastened to the bottom of the container engages the collar 316 on the shaft 18, guides the container as it moves up and down in accordance with the position of the cam, and keeps the arm 46 and shaft 18 in alinement.

At rest, the crosshead 92 is at the front of the machine, as shown in Fig. 1, being held in this position by the latch 278. In this position the counter clamping means 130 are held disen-

gaged from the substantially V-shaped block 126 by the stop-disk 234, as represented in Fig. 5; hence, the machine is in readiness for receiving an uncoated counter to be operated upon. The counter is placed astride the counter holding and clamping blocks 84 and 126 and is pushed rearwardly to bring the spring-pressed rounded end 158 (Fig. 10) of the block 126 in engagement therewith. While the counter is held in this position, the operative pulls the rod 236 by means of the knob 238, or by the operation of a treadle connected to the lever 241, which causes the collar 286 (Fig. 5) to lift the arm 288 thereby to release the latch 278. The rod 236 also shifts the drive belts, whereupon the crosshead begins to move toward the rear of the machine. As the crosshead leaves its initial position, the wedge block 174 disengages the stop disk 234, allowing the clamping plates 130 to be drawn by the springs 142, 144 into clamping position to hold the counter in place. During the initial movement of the crosshead the portion *a* (Fig. 9) of the overhead cam 312 holds the brush 14 in engagement with the brush 16 and the receptacle 42 in engagement with the brush 14, thus supplying both brushes. The counter holding and clamping means approaches the brushes, holding the counter with one leg at substantially 20° to the horizontal and as the leading end of the leg approaches the entrance side of the brushes the cam 312 moves the upper brush 14 away from the lower brush 16. Hence, the leading end of the leg of the counter enters between the brushes without engaging either of them. As the linear movement continues, the inner surface of the leg engages the brush 16 and simultaneously the cam depresses the brush 14 so that it engages the outer surface of the leg. Since the leg slopes, the cam 312 is so formed that the brush 14 is moved downwardly to follow the slope of the leg during the remainder of the movement of the counter until the rounded end thereof is reached, whereupon it is held stationary. Rotation of the counter is effected by the lever 292 which arrests the linear movement of the crosshead until the other leg of the counter is brought into a reversely inclined position, that is, so that it makes an angle 20° to the horizontal, whereupon the screw 304 on the disk 108 (Fig. 6) releases the lever 292 and linear movement is resumed, thus drawing the other leg between the brushes. During this period the brush 14 is moved upwardly along the slope of the other leg and out of engagement with the other leg near its end portion simultaneously with the movement of the inside of the leg out of engagement with the brush 16. The crosshead continues its movement to the rear of the machine where the bolt 276 (Figs. 1 and 9) on the crosshead base strikes the lever 240 and shifts the drive belts, reversing the direction of movement of the chains 106 and 188 so that the crosshead is moved back toward the front of the machine in the same manner that it moved toward the rear of the machine. Near the front of the machine the depending boss 284 (Fig. 5) on the crosshead strikes the collar 286 and thereby moves the rod 236 which, in turn, moves the lever 240 to a neutral position, thereby stopping the machine. The latch 278 also rides over the pin 282 to hold the crosshead in rest position. At the same time, the stop-disk 234 strikes the wedge block 174 and disengages the clamping means 130, whereupon the rounded end 158 of the block 126 disengages the counter from the counter supporting

and clamping blocks 84 and 126. This completes the cycle of operation of the machine until the rod 236 is again actuated.

Having described my invention, what I claim as new and desire to secure by Letters Patent of the United States is:

1. In a machine for applying adhesive to a premolded counter having diverging legs, applicator means, means for supporting the counter, means for causing relative movement of said means lengthwise of a leg in such a direction as to bring together the counter and the applicator means first at a point spaced from the end of one leg of the counter and then to move one over the other to spread the adhesive over an adjacent portion of the counter, leaving a clean margin at the first end.

2. In a machine for applying adhesive to a premolded counter having diverging legs joined by a rounded back part, an applicator, and means for supporting and bodily moving the counter in a predetermined path to advance first one leg and then the other across the applicator, means for so positioning said counter with respect to said supporting and moving means that the marginal portions adjacent to the free ends of said legs lie outside the field of action of the applicator.

3. In a machine for applying adhesive to a premolded counter having diverging legs joined by a rounded back part, an applicator, and means for moving the counter linearly to advance first one leg and then the other across the applicator and to hold the legs tilted at an angle to the direction of linear movement so that the marginal portions at the free ends lie outside the field of action of the applicator.

4. In a machine for applying adhesive to a premolded counter having diverging legs joined by a closed, rounded back part, a cylindrical applicator, means for supporting the counter, and means for causing relative movement of said means to bring together the counter and the applicator at a point spaced from the end of one leg, then to move one over the other to spread adhesive over an adjacent portion of the counter, and finally to separate the counter and the applicator at a point spaced from the end of the other leg leaving clean margins at the ends of both legs.

5. In a machine for applying adhesive to a premolded counter having diverging legs joined by a closed back part, a cylindrical brush for applying adhesive to the inner surface of the counter, and means for moving the counter linearly to advance first one leg and then the other across the applicator with the legs tilted at such an angle with respect to the direction of linear movement that those portions of the legs adjacent to their ends lie outside the radius of the brush.

6. In a machine for applying adhesive to a premolded counter having diverging legs joined by a rounded back part, a cylindrical applicator, means for moving the counter with respect to the applicator to bring first one leg and then the other into contact with the applicator and for holding the legs of the counter at corresponding but reverse angles to the direction of movement during the application of adhesive thereto so that the projection of the applicator on the counter lies within the ends of the legs.

7. In a machine for applying adhesive to a premolded counter having diverging legs joined by a closed, rounded back part, an applicator, and

means for moving the counter to advance first one leg thereof across the applicator until the closed end is substantially in engagement with the applicator and then to turn the counter and to draw the other leg across the applicator, said means being arranged to hold the legs at such angles with respect to the direction of movement that the initial line of contact between the advancing leg and the applicator is parallel to and spaced from its leading end and the final line of contact between the withdrawn leg and the applicator is parallel to and spaced from its trailing end.

8. In a machine for applying adhesive to a premolded counter having diverging legs joined by a closed, rounded end, a bodily movable applicator, means for moving the counter linearly to advance first one leg and then the other in a path contiguous to the applicator, and means for moving said applicator into said path of said one leg at a predetermined time after the leading end has advanced beyond the field of action of the applicator and for moving it out of said path at a predetermined time before the trailing end of said other leg has reached the field of action of the applicator.

9. In a machine for applying adhesive to a premolded counter having diverging legs, a bodily movable applicator, means for moving the counter linearly to advance first one leg and then the other in a path contiguous to the applicator, and means for moving the applicator into and out of contact with said legs in timed relation to the movement of the counter so that the applicator engages said one leg after the leading end thereof has passed beyond the field of action of the applicator and disengages the trailing end of said other leg before it reaches the field of action of the applicator.

10. In a machine for applying adhesive to a premolded counter having diverging legs, a bodily movable applicator, means for moving the counter linearly to advance first one leg and then the other in a path contiguous to the applicator, and means associated with the first-named means for moving the applicator into and out of contact with said legs in timed relation to the movement of the counter so that the applicator engages said one leg after the leading end thereof has passed beyond the field of action of the applicator and disengages the trailing end of said other leg before it reaches the field of action of the applicator.

11. In a machine for applying adhesive to a premolded counter having diverging legs, a bodily movable applicator, means for moving the counter linearly to advance first one leg and then the other in a path contiguous to the applicator, and cam means associated with said first-named means and operable thereby for moving the applicator into and out of contact with said legs in timed relation to the movement of the counter so that the applicator engages said one leg after the leading end thereof has passed beyond the field of action of the applicator and disengages the trailing end of said other leg before it reaches the field of action of the applicator.

12. In a machine for applying adhesive to a premolded counter having diverging legs, a bodily movable applicator, means for moving the counter linearly to advance first one leg and then the other in a path contiguous to the applicator, means for normally holding the applicator out of said path, and means for moving the applicator into said path in timed relation to the movement of the counter so that the applicator en-

gages said one leg after the leading end thereof has passed beyond the field of action of the applicator and for permitting said second means to move the applicator out of said path to disengage the trailing end of said other leg before it reaches the field of action of the applicator.

13. In a machine for applying adhesive to a premolded counter having diverging legs joined by a rounded, closed end, a bodily movable applicator, means for moving the counter linearly to advance first one leg and then the other in a path contiguous to the applicator, and cam means for moving the applicator to and from the path of movement and in such timed relation to the movement of the counter that the applicator is moved into engagement with the surface of said first leg at a point adjacent to the leading end, is held in contact with said leg, with said closed end and with said other leg until a corresponding point adjacent to the end of said other leg is reached, whereupon it is moved out of contact with said other leg.

14. In a machine for applying adhesive to a premolded counter having diverging legs joined by a rounded, closed end, a bodily movable applicator, means for moving the counter linearly in a path contiguous to the applicator to advance first one leg along said path at an angle to the direction of movement, for rotating the counter as its closed end reaches the applicator to bring the other leg into a corresponding angular position and to continue the movement of the counter in the same direction, rounded end first, to advance the other leg along said path, and cam means for moving the applicator in timed relation to the movement of the counter into the path of the counter to cause the applicator to engage said one leg back of its leading end, for maintaining it in contact with the inwardly and outwardly sloping legs, and for moving it out of the path to disengage said other leg near its trailing end.

15. In a machine for applying adhesive to a premolded counter having diverging legs joined by a rounded, closed end, means for moving the counter in a linear path with first one leg and then the other in a predetermined angular position with respect to the path of movement of the counter, an applicator brush mounted for rotation on a horizontal shaft, said shaft being bodily movable, and means for moving said shaft to and from the path of movement of the counter in timed relation to the movement of the counter to cause the brush to contact the counter near the leading end of said one leg, maintaining it in contact with the inwardly and outwardly sloping surfaces of said legs, and moving it out of contact with said other leg near the trailing end.

16. In a machine for applying adhesive to a premolded counter having diverging legs joined by a rounded, closed end, means for moving a counter in a linear path with first one leg and then the other in a predetermined position with respect to the path of movement of the counter, an applicator brush mounted for rotation on a shaft, said shaft being mounted for bodily movement to and from the path of movement of the counter, and cam means for moving the shaft toward and away from the counter in timed relation to the movement of the counter to compensate for the slope of the legs, said cam means being arranged to establish contact of the applicator with the counter back of the leading end of said one leg and to break contact with the

counter before the trailing end of said other leg is reached.

17. In a machine for applying adhesive to a premolded counter having diverging legs joined by a rounded, closed end, a pair of applicators adapted to engage the opposite surfaces of the legs of the counter passed between them, means for moving the counter linearly to advance first one leg and then the other between the applicators, said means being adapted to hold the legs of the counter at such angles with respect to the direction of movement that the inside surfaces of the legs adjacent to their ends lie beyond the field of action of the applicator adapted to coat the inner surface of the counter, and means for bodily moving the applicator adapted to coat the outside surface of the counter into and out of contact with the outer surfaces of the legs in such timed relation that the last applicator engages and disengages the outer surfaces of the legs at points substantially opposite the engagement and disengagement of the inside surfaces of the legs with the first applicator.

18. In a machine for applying adhesive to a premolded counter having diverging legs, two applicators, an adhesive container adjacent to one of the applicators and adapted to supply it with adhesive, and automatic means to present the work between the applicators and to move the applicators together to transfer adhesive from one to the other and then to separate them to admit the work.

19. In a machine for applying adhesive to a premolded counter having diverging legs, two applicators, an adhesive container adjacent to one of the applicators and adapted to supply it with adhesive, and automatic means to present the work between the applicators and to move the applicators in timed relation to the movement of the work to transfer adhesive from one to the other and then to separate them to admit the work.

20. In a machine for applying adhesive to a premolded counter having diverging legs, a support for the counter having a contour which is substantially complementary to the inside contour of the counter whereupon a counter placed therein will closely engage the same, releasable means for holding a counter on the support during the application of adhesive, and means associated with the support automatically to disengage a mounted counter from said support after the release of the holding means.

21. In a machine for applying adhesive to a premolded counter having diverging legs, a support for the counter having a contour which is substantially complementary to the inside contour of a counter whereupon a counter placed thereon will closely engage the same, clamping means for holding the counter in engagement with said support, means for releasing said clamping means, and means for simultaneously disengaging the counter from said support.

22. In a machine for applying adhesive to a premolded counter having diverging legs, a support for the counter having a contour which is substantially complementary to the inside contour of the counter whereupon a counter placed thereon will closely engage the same, means for clamping the counter on said support, and means associated with the support which is operable to disengage the counter from said support, said means being rendered inoperative by the engagement of said clamping means to hold the counter on the support and being rendered oper-

ative by the disengagement of said clamping means from said support.

23. In a machine for applying adhesive to a premolded counter having diverging legs, a support for the counter having a contour which is substantially complementary to the inside contour of the counter whereupon a counter placed thereon will closely engage the same, clamping means for holding the counter on the support, means for rendering said clamping means operative and inoperative, and spring-actuated means associated with said support and operable upon movement of the clamping means into inoperative position to disengage the counter from said support.

24. In a machine for applying adhesive to a premolded counter having diverging legs, a two-part support the elements of which when contiguous form a member which has a contour which is substantially complementary to the inside contour of a counter whereupon a counter placed thereon will closely engage the same, clamping means associated with one part of said support and operable to clamp the counter on said support thereby to hold the two parts in contiguous relation, and means for yieldably urging the other part away from said one part, said means being rendered effective upon release of said clamping means to disengage the counter from said one part.

25. In a machine for applying adhesive to a premolded counter having diverging legs, a pair of applicator brushes one of which is fixed and the other of which is movable to and from the fixed brush, means for moving the legs of the

15

counter in succession between the brushes, means for holding the movable brush in engagement with the fixed brush for a predetermined time and for thereafter moving it in a predetermined path in timed relation to the movement of the counter to cause it to engage predetermined portions of the legs of the counter, a container adjacent to the movable brush, and means for holding the container in tangential relation with the movable brush during the time the latter engages the fixed brush and for holding it at a fixed position with respect to the median of the range of movement of the movable brush during the remainder of its movement.

26. In a machine for applying adhesive to a premolded counter having diverging legs joined by a closed, rounded, back part, a pair of applicators adapted to treat the inside and outside surfaces of the counter, counter-supporting means for moving the counter linearly to advance first one leg and then the other in a path contiguous to one applicator, said supporting means holding the legs during their linear movement in such a position that their inner surfaces near their ends lie beyond the field of action of said one applicator, and means for moving the other applicator to and from the path of movement of the counter to bring it into coating relation with the outer surface thereof in timed relation to the movement of the counter, thereby to cause it to engage and disengage the outer surfaces of the legs at points corresponding to the engagement and disengagement of the inner surfaces of the legs with said first applicator.

CHARLES MARTIN BAGSHAW.
